John F. Haestedt

UNITED STATES PATENT OFFICE.

PERCIVAL EVERITT, OF LONDON, ENGLAND.

COIN-OPERATED LOCK.

SPECIFICATION forming part of Letters Patent No. 374,785, dated December 13, 1887.

Application filed June 16, 1887. Serial No. 241,494. (No model.)

To all whom it may concern:

Be it known that I, PERCIVAL EVERITT, a subject of the Queen of Great Britain, and a resident of London, England, have invented 5 certain new and useful Improvements in Coin-Operated Locks, and is applicable to water and other closets, lavatories, and the like, of which the following is a specification.

Figure 1 represents the inside of a door of a water or other closet, and to this door I apply 10 the devices whereby the door, which is normally locked, may be unlocked by the deposit from outside the door into a receptacle inside the door, through a suitable slit or slot made 15 in the door, of a coin, token, or the like. Fig. 2 is a top view showing the door partly in section, and also showing a small part of a door-frame in section.

The parts not necessary to be described are 20 omitted from the drawings.

On the inside of the door A, I arrange a lock-bolt, a, and a latch-bolt, b, each of which is secured to its respective rod or bar a' or b', and these bolts are shown in the position usually 25 styled "half-shot," and c d are bell-crank levers, one end, c', of lever c being pivoted to rod a', and one end, d', of lever d being pivoted to rod b'. The other arm, c'', of lever c is slotted to receive the lower end of a link, e, 30 which is jointed to the shorter arm of a lever, f, which carries at its other extremity the coin or token receptacle j. The upper or remaining end or arm of lever d is pivoted at d'' to a vertically-movable rod, g, held in a 35 guide, h, and is provided with a pin, i, projecting backward toward the door. The levers are shown at about the center of their travel. Any suitable slit, k, cut through the door, with or without a chute connected to it, serves to 40 guide into the receptacle j the coin or other token of predetermined weight and size. The weight of the coin carries down the lever f,

and the receptacle discharges its coin in the same manner as in my application, Serial No. 226,251, allowed on or about April 29, 1887, 45 or as is usual in other devices of such character; and the devices for effecting such discharge need not therefore be here repeated.

Now, upon depositing the coin of proper size and weight in the slot k it passes into the receptacle j, and by its weight carries down its longer arm (this lever being fulcrumed at f'.). This movement lifts link e, and by the means of pin e' thereon the arm c'' of lever c is raised, and thereby its other arm, c', draws 55 backward bar a and its bolt a'. When the weight of the coin has carried lever f low enough to bear upon the pin i on the slide-rod g, this movement of rod g actuates the arm d'' of lever d, and either draws back or permits a 60 person on the outside of the door, by turning the ordinary latch knob or handle, to open the door. When the coin, after the receptacle has descended, has dropped out of such receptacle, the lever f, being thus lightened, goes back to 65 its normal position, and the bolt a' also is forced back to a position which again locks the door, and which again requires the deposit of a proper coin or token before it can be opened. 70

I claim--

The combination, with a door having a coin-receiving opening, of a coin receiving and discharging box, its supporting-lever, the link e, levers c d, rods or bars a' b' b', and the slide-rod g, all substantially as and for the purpose set forth. 75

Signed at New York city, in the county of New York and State of New York, this 13th day of June, A. D. 1887.

PERCIVAL EVERITT.
